US0D1099926S

(12) **United States Design Patent** (10) **Patent No.:** **US D1,099,926 S**
Foley et al. (45) **Date of Patent:** **** Oct. 28, 2025**

(54) **DISPLAY SCREEN OR PORTION THEREOF WITH GRAPHICAL USER INTERFACE**

(71) Applicant: **Peloton Interactive, Inc.**, New York, NY (US)

(72) Inventors: **John Foley**, New York, NY (US); **Thomas Cortese**, Summit, NJ (US); **Yu Feng**, New York, NY (US); **Hisao Kushi**, Santa Monica, CA (US)

(73) Assignee: **Peloton Interactive, Inc.**, New York, NY (US)

(**) Term: **15 Years**

(21) Appl. No.: **29/910,028**

(22) Filed: **Aug. 14, 2023**

CPC G06F 1/163; G06F 19/3418; G06F 3/0481; G06F 3/0482; G06F 3/0483; G06F 3/0485; G06F 3/0487; G06F 3/0485; G06F 3/048; G06F 3/0488; G06F 3/0486; A61B 5/0205; A61B 5/6801; A61B 5/681; A61B 5/6895

(57) **CLAIM**

The ornamental design for a display screen or portion thereof with graphical user interface, as shown and described.

DESCRIPTION

The FIGURE is a front view of a display screen or portion thereof with graphical user interface showing the new design.

The outermost broken line rectangle showing the display screen or portion thereof, and all other broken lines showing portions of the graphical user interface, illustrate portions of the article and form no part of the claimed design.

1 Claim, 1 Drawing Sheet
